(57)

CLAIM

The ornamental design for a wheeled cart, as shown and described.

DESCRIPTION

FIG. 1 is a top, front, right-side perspective view of a wheeled cart;

FIG. 2 is a back, bottom, left-side perspective view thereof;

FIG. 3 is a top, back, left-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof; and,

FIG. 9 is a bottom view thereof.

The dashed broken lines depict portions of the wheeled cart that form no part of the claimed design. The dot-dashed broken lines represent boundaries of the claimed design and form no part of the claimed design.

1 Claim, 9 Drawing Sheets
